UNITED STATES PATENT OFFICE.

CHARLES H. HILL, OF LOMBARDVILLE, ILLINOIS, AND JAMES T. RYAN,
OF MANNING, IOWA.

ADJUSTABLE SEAT-LIFT CULTIVATOR.

SPECIFICATION forming part of Letters Patent No. 297,933, dated April 29, 1884.

Application filed December 31, 1883. (No model.)

To all whom it may concern:

Be it known that we, CHARLES H. HILL and JAMES T. RYAN, of Lombardville and Manning, in the counties of Stark and Carroll, in 5 the States of Illinois and Iowa, respectively, have invented an Improved Cultivator; and we do hereby declare that the following is a full, clear, and exact description thereof, reference being had to the annexed drawing, 10 making a part of this specification, in which like letters of reference refer to like parts, and in which the figure represents a perspective view of the machine.

This invention is in that line of cultivators 15 in which the driver is enabled to ride thereon, and, by means of various mechanisms, control the paths of the cultivator-blades.

Our invention consists, essentially, of a frame pivoted near its center to the axle-tree of the 20 cultivator, a seat fixed upon the rear end of said frame, and connections joining the opposite end of said frame to the plow-blade frames pivoted as in other machines of the class.

In the drawing, A is the frame, pivoted at 25 B to the axle-tree C, and having at its rear end the driver's seat D. The beams E, to which are secured the plows F, are pivoted at E' to the swivels G, depending from the framework H, by means of the studs G', as in other 30 cultivators of the kind. The forward end of the frame A is connected by chains or other couplings to the beams E at S', so that a downward movement of the seat D raises the plows F. The driver, sitting in the seat D, rests his 35 feet upon the beams E, they being retained in place thereon by means of stirrups V. The leverage of the frame A is so altered by shifting the fulcrum-bolt B' that the weight of the driver upon the seat D shall a little more than 40 counterbalance the beams E and their attached plows F. Therefore, by resting more or less of his weight upon both or either of the beams E their vertical positions are changed to suit the inequalities of the ground.

45 As shown in the drawing, the bearings B have several bolt-holes through them, and in the side beams of the frame A are similar holes in line therewith. By shifting the bolts B' from one to the other of the bolt-holes, the 50 leverage of the said frame is, without chang-

ing its position, increased or diminished, as desired. This adjustment is necessitated by the variations in the weights of the drivers.

In case a boy is running this cultivator, the weight of the beams E and attached blades 55 might overbalance him and tend to throw him up out of reach of the said beams E. To prevent such upward movement, we provide the lever L, whose lower end projects beneath the cross-bar N. By means of the toothed disk M, 60 to which said lever is pivoted, and suitable catch to engage therewith, the said lever L is locked at any desired angle and the frame A held thereby.

To permit one beam E to rise as the other 65 one is lowered, or even retained at the same level, or the said beams to be swung from side to side, we suspend said beams E from the opposite ends of a single chain, which passes over a pulley secured to the front end of the pivoted 70 frame A. By this construction the chain S can give way to either one beam or the other, and so permit the desired variation in their heights.

To adapt this cultivator to drivers of different stature the chain S can be lengthened or shortened by hooking different ones of the links composing it to the hooks S', by which it is held to the beams E. 75

Although we have shown in the drawing 80 and described a chain, S, to connect the frame A to the beams E, we do not restrict ourselves to the same. A wire rope, strap, or other flexible bond can of course be substituted for the chain shown.

To permit the variable vertical and horizontal movements of the two beams E relatively to each other, there may be several modifications of the device which we have shown. In place of the pulley P and single chain S, a 90 short bar may be pivoted at its center to the front end of the frame A, and rods, chains, or cords extend from the ends of said bar to the beams E. The former device we deem, however, the more preferable. 85

By means of the yoke R, secured at its ends to the beams E, these latter are retained at the same distance apart. The stirrups R' have two or more bolt-holes, to enable the beams E to be adjusted to suit any width of row in 100

which the corn may be planted. These stirrups R' being held to the beams E by a vertical bolt, and the yoke R being pivoted by a horizontal pin or bolt to said stirrups, said 5 yoke is held to said beams by a form of universal joint, which permits the required swinging of said beams.

What we claim as our invention is—

1. In a cultivator, a frame centrally pivoted 10 to the axle or frame of the cultivator, and having a seat upon its rear end, in combination with a pulley secured to the forward end of said pivoted frame, and a chain or other flexible bond passing over said pulley and fastened 15 at its ends to the plow-beams of the cultivator, whereby the weight of the driver in said seat shall support said plow-beams and permit them unequal and opposite vertical motion, as set forth.
- 20 2. The frame A, seat D, and bearings B, in combination with the pulley P, chain S, and the beams E of a cultivator, for the purpose described.
- 25 3. The frame A, seat D, bearings B, and pulley P, in combination with the chain S, hooks S', beams E of a cultivator, the yoke R, and stirrups R', substantially as specified.

4. In a cultivator, the frame A, having several bolt-holes therethrough, in combination with the bearings B, having corresponding 30 bolt-holes, and pivoted to the axle or frame of a cultivator, and the bolts or pins B', whereby the leverage of said frame A may be changed without altering the longitudinal position of the same.

35 5. The combination, in a cultivator, of a frame centrally pivoted to the axle or frame thereof, and having a seat upon its rear end, and means whereby the plow-beams are suspended from the front end of the said pivoted 40 frame, so that these plow-beams shall counterpoise each other and enable the elevation and depression of one to oppositely affect the other, for the purpose set forth.

In testimony that we claim the foregoing invention we have hereunto set our hands this 45 27th day of December, A. D. 1883.

CHARLES H. HILL.
JAMES T. RYAN.
